UNITED STATES PATENT OFFICE.

ELMER E. HAUER, OF SPRINGFIELD, OHIO, ASSIGNOR, BY MESNE ASSIGNMENTS, TO ELLIOTT COMPANY, OF PITTSBURGH, PENNSYLVANIA, A CORPORATION OF PENNSYLVANIA.

TUBE-CLEANING APPARATUS.

1,185,198.

Specification of Letters Patent. Patented May 30, 1916.

Application filed November 25, 1912. Serial No. 733,477.

To all whom it may concern:

Be it known that I, ELMER E. HAUER, a citizen of the United States, residing at Springfield, in the county of Clark and State of Ohio, have invented certain new and useful Improvements in Tube-Cleaning Apparatus, of which the following is a specification, reference being had therein to the accompanying drawings.

10 My invention relates to tube cleaning devices, and more particularly to devices of this kind that are employed in cleaning bent tubes, although they may be used in straight tubes.

15 The object of my invention is to simplify and lessen the cost of production by the use of fewer parts so arranged that the device will more readily pass through bent tubes and give more efficient service.

20 With these and other objects in view my invention consists of the constructions and combinations hereinafter described and set forth in the claims.

In the drawings Figure 1 is a longitudinal view partly in section, of a rotary motor, cleaner head and universal coupling, Fig. 2 is a like view taken at right angles thereto and showing a different form of cleaner head, Figs. 3 and 4 are enlarged views partly in section taken at right angles to each other and in different operative positions, of the cleaner head and coupling shown in Fig. 1 and Fig. 5 is a cross-section taken on the line 5—5 of Fig. 3.

25 Any form of a rotary motor may be employed, but for the purpose of illustration a turbine is shown having a casing 1 adapted to travel through a tube. The rear head 2 is hollow forming a chamber having a screw-threaded inlet 3 in which a coupling 3^a of a supply conduit or hose is secured to supply the motive agent, which passes through inclined ports 4 of a disk 5 to buckets 6 of a wheel 7 and is discharged 30 through the ports 8 in a well known manner. The wheel 7 is fixed to a shaft 9 by an intermediate hardened hub 10. Said shaft is journaled in bearings 11 and is screw-threaded at its outer end 12.

35 A universal coupling having end-pieces 13 with oppositely disposed longitudinally extending ears 14, has the ears of the respective pieces joined together by webs 15 with their inner walls inclined in opposite directions as shown. A connecting member

16 is pivoted at its respective ends by pivots 17 within the recesses formed by the ears and webs of the respective end-pieces. One end of the coupling is secured to the screw-threaded end 12 of the motor shaft and to give increased efficiency to the cleaner head I preferably arrange this connection with the axis of the coupling to one side of the axis of the driving shaft as particularly shown by the lines *a—a* and *b—b* in Fig. 1. 65

It has been common to provide couplings having the end-pieces with oppositely disposed longitudinally extending ears without the ears of the respective pieces being joined by webs; but to give them the necessary strength when employed in driving tube cleaners it has been necessary to make them of wrought material. By joining the ears with webs as described the parts are given sufficient strength so that they can be 70 cast, thereby materially reducing the cost. Furthermore the webs with their oppositely inclined walls allow sufficient play, and yet limit the movement of the coupling so that the respective parts will not lock when in 75 extreme angular position as will sometimes happen in couplings having the ears without the webs. It will be further noted especially by reference to Figs. 3 and 4 that the connecting member 16 is made of sufficient length so that the ears of the respective end-pieces will not meet even though the webs to join the ears of the respective end-pieces are not employed; but I preferably employ the webs and also make the 80 connecting member of sufficient length to prevent the meeting of the end-pieces. 85

Any type of cleaner head may be employed with the universal coupling and the means for driving same; but when the motor is 90 adapted to travel through the tube with the cleaner and is employed in cleaning bent tubes it is essential that the device be as short as possible, and with this end in view I have devised and shown in Figs. 100 1, 3 and 4 a cleaner head formed integral with and as a part of the outer or free end of the universal coupling, the same being preferably a hard metal casting having peripheral cutting edges 18. It will be seen 105 that by making the cleaner head in a single piece with the outer or free end of the coupling a connection is thereby avoided and the device is shortened.

When it is desired to employ a cleaner 110

head made separate from and secured to said coupling, the connection can be made in any suitable way, as for instance as shown in Fig. 2, where a well known form of cleaner head is shown secured to a screw-threaded reduced portion 19 of the free end of the coupling.

Having thus described my invention I claim:—

- 10 1. In a tube cleaning apparatus, the combination of a motor adapted to travel through a tube and a coupling having end members, one of which is secured to the motor shaft and the other having cutters, each of said end members having a pair of ears the inner walls of which extend longitudinally in parallel planes, the ears of the respective ends being joined together by webs forming oppositely disposed inclined walls, the inclined walls 35 of one end being arranged at right angles to those of the other end and a connecting member pivoted in recesses formed by said ears and webs with its walls abutting the inner walls of said ears and free to swing 40 against the inclined walls of said webs, substantially as described.
- 15 2. In a tube cleaning apparatus, the combination of a driving shaft and a coupling having end members, one of which is secured to said shaft and the other free end having cutters, each of said end members 30 having a pair of ears the inner walls of which extend longitudinally in parallel planes, the ears of the respective ends being joined together by webs forming oppositely disposed inclined walls, the inclined walls 35 of one end being arranged at right angles to those of the other end and a connecting member pivoted in recesses formed by said ears and webs with its walls abutting the inner walls of said ears and free to swing 40 against the inclined walls of said webs, substantially as described.
- 20 3. In a tube cleaning apparatus, the combination of a motor adapted to travel through a tube and a coupling having end members, one of which is secured to the motor shaft and the other having cutters, each of said end members having a pair of ears the inner walls of which extend longitudinally in parallel planes, the ears of the respective ends being joined together by webs forming oppositely disposed inclined walls, the inclined walls 35 of one end being arranged at right angles to those of the other end and a connecting member pivoted in recesses formed by said ears and webs with its walls abutting the inner walls of said ears and free to swing 40 against the inclined walls of said webs, substantially as described.
- 25 4. In a tube cleaning apparatus, the combination of a motor adapted to travel through a tube and a coupling having end members, one of which is secured to the motor shaft and the other having cutters, each of said end members having a pair of ears the inner walls of which extend longitudinally in parallel planes, the ears of the respective ends being joined together by webs forming oppositely disposed inclined walls, the inclined walls 35 of one end being arranged at right angles to those of the other end and a connecting member pivoted in recesses formed by said ears and webs with its walls abutting the inner walls of said ears and free to swing 40 against the inclined walls of said webs, substantially as described.

2. In a tube cleaning apparatus, the combination of a driving shaft and a coupling having end members, one of which is secured to said shaft and the other free end having cutters, each of said end members 30 having a pair of ears the inner walls of which extend longitudinally in parallel planes, the ears of the respective ends being joined together by webs forming oppositely disposed inclined walls, the inclined walls 35 of one end being arranged at right angles to those of the other end and a connecting member pivoted in recesses formed by said ears and webs with its walls abutting the inner walls of said ears and free to swing 40 against the inclined walls of said webs, substantially as described.

In testimony whereof I have hereunto affixed my signature in the presence of two witnesses:

ELMER E. HAUER.
